DESIGN FOR A TEXTILE FABRIC OR SIMILAR ARTICLE

Application filed October 14, 1932. Serial No. 45,331. Term of patent 3½ years.

To all whom it may concern:

Be it known that I, HERMAN S. MURRAY, a citizen of the United States of America, residing at Woodmere, Long Island, New York, have invented a new, original, and ornamental Design for a Textile Fabric or Similar Article, of which the following is a specification, reference being had to the accompanying drawing, forming a part thereof.

The figure is a plan view of a textile fabric showing one-fourth of the unit of my new design. The portion shown in detail between

the dot and dash lines A—B and C—B is repeated throughout the entire unit. The other three corners bearing the same design are arranged in proper relation to the detailed illustration to complete the pattern. The drawing is lined to indicate shading.

I claim:

The ornamental design for a textile fabric or similar articles as shown and described.

In testimony whereof I have signed this specification.

HERMAN S. MURRAY.
